M. KOSSMANN.
LAMP SHADE HOLDER.
APPLICATION FILED APR. 17, 1918.

1,278,808.

Patented Sept. 10, 1918.

UNITED STATES PATENT OFFICE.

MAX KOSSMANN, OF BROOKLYN, NEW YORK, ASSIGNOR TO ROBERT FINDLAY MANUFACTURING COMPANY, INCORPORATED, OF NEW YORK, N. Y., A CORPORATION OF NEW YORK.

LAMP-SHADE HOLDER.

1,278,808.

Specification of Letters Patent. Patented Sept. 10, 1918.

Application filed April 17, 1918. Serial No. 229,088.

To all whom it may concern:

Be it known that I, MAX KOSSMANN, a citizen of the United States of America, residing at Brooklyn, Kings county, State of New York, have invented certain new and useful Improvements in Lamp-Shade Holders, of which the following is a full, clear, and exact description.

This invention relates to improvements in lamp-shade holders, but more particularly to the inverted variety employing a hemisphere or lower globe and a reflector located above the same, the invention having for its particular object to provide a holder or bracket to securely but detachably retain the inverted hemisphere, said holder or bracket being arranged to coöperate with one of the elements of the lamp assembly to perform its function in supporting the said inverted globe.

In the accompanying drawing, to which reference will be had, in connection with the following detailed description:

Figure 1, illustrates a sectional view partly in elevation of a lamp assembly a part of which constitutes my improved holder;

Fig. 2 is an enlarged fragmentary sectional view, the section being taken on a line 2—2 in Fig. 1 before the cap is pressed down; and

Fig. 3 is a perspective view of my improved holder.

The type of lamp to which my invention applies, comprises an inverted globe 4, a reflector 5 therefor, and a cap 6 which supports the lamp assembly, said cap being attached to any suitable suspension means, a tubular conduit 7 for instance. The cap 6 is of the usual cupped formation, having a depending side-wall 6^a and a socket 8 for the attachment of a suitable supporting medium for the lamp assembly. The cap 6 will be provided with the usual clamping screws 9 which pass through the wall 6^a and engage the neck 10 of the reflector 5. As this is a common expedient, it has not been illustrated in greater detail.

My improvement is embodied in a holder or bracket 11 consisting of a plurality of yieldable or flexible arms 12, 13 and 14, secured at their lower end to a cup-shaped base-member 15, to which a cap 16 is connected by means of a threaded stud 21 and

rotatable nut 17. The lower end of the lower globe 4 is supported by the lower cap 16. To insert the lower end of the globe in said cap, the nut 17 will be manipulated to permit the lower cap 16 to be pulled away from the lower end of the holder 11, sufficiently for the insertion thereinto of the lower end of the globe 4, after which the cap 16 will be adjusted and maintained by the nut 17.

The upper end of each arm 12, 13 and 14 is bent over or hooked as at 18 to provide a downwardly extending yieldable projection 19 to engage the flange 6^a of the upper cap 6. As can be seen in Figs. 1 and 2, the hooked ends of the arms engage the upper beading or edge 20 of the globe 5, the yieldable extensions 19 being located exteriorly of the reflector 5 and in engagement with the flange 6^a of the cap 6. When the lamp is assembled, the cap 6 will engage the projections 19, said projections being at such a time under a slight tension; hence the holder 11 will be firmly held against rotation or jarring. Owing to the fact that the upper end of each arm 12, 13 and 14 is thus firmly held, the holder can be adjusted to position the lower globe centrally of the reflector 5. To adjust the holder, the arms 12, 13 and 14 will be bent or manipulated in any desirable manner. The yieldable projections 19 of the hooked ends of the arms 12, 13 and 14, are provided with lips 22, which engage the lower edge of the flange 6^a of the cap 6.

The particular object of my invention is to provide a holder arranged to coöperate with one of the elements of the lamp assembly, preferably the upper cap, that will be firmly held against a shifting action after the upper cap has been applied to the reflector and secured by its set-screws.

It will be apparent from an inspection of Fig. 2 that the extensions 19 of the hangers 12, 13 and 14 will be forced inwardly by the flange of the cap when said cap is pressed down, thereby forcing the adjacent ends of the hangers firmly into contact with the edge 20 of the reflector 5 and causing the beading 23 to enter the recess 24 adjacent the outer end of the extensions 19, thereby preventing premature separation of the cap and holder, irrespective of the set-screws, which might loosen.

What I claim as my invention is:
In a shade-holder, a plurality of flexible
arms, means at one end of each arm to sup-
port a globe, the opposite end being turned
over upon itself to form a hook having an
extension, said extension being provided
with a loop to receive the beading of a cap.

Signed at New York city, N. Y., this
12 day of April, 1918.

MAX KOSSMANN.
